UNITED STATES PATENT OFFICE.

JAMES T. HAMBAY, OF NEW YORK, N. Y.

RAILWAY-SIGNAL.

1,299,718.

Specification of Letters Patent.

Patented Apr. 8, 1919.

Application filed September 25, 1912. Serial No. 722,182.

To all whom it may concern:

Be it known that I, JAMES T. HAMBAY, a citizen of the United States, residing at the city of New York, borough of Manhattan, county and State of New York, have invented a certain new and useful Railway-Signal, of which the following is a specification.

This invention is a new signal operating mechanism, and the object of the invention is to operate signals with pronounced economy, efficiency and safety. Moreover, the operation is such that the moving parts are subjected to only a minimum of momentum and shock, thereby greatly increasing the durability of the mechanism. Furthermore, the speed of operation is very considerably greater than that of the apparatus heretofore used, and certain of the important automatically operating parts can be so controlled as to regulate the speed at which the signal-blade moves in going to either the danger or safety position.

The salient advantage of the invention consists in its great economy of operation, and to secure this advantage the invention embodies mechanism whereby a very considerable portion of the energy developed when the signal-blade falls by gravity to a danger position is stored up and made available to assist in returning the signal-blade to a safety position.

While the foregoing result may be attained either electrically or mechanically, I prefer to employ any one of the usual electrically operating mechanisms now or heretofore used, and to use, in conjunction therewith supplemental mechanism whereby the gravity movement of the signal-blade to danger operates to elevate a weight or weights, or otherwise store energy, which energy is subsequently utilized to assist in returning the signal-blade to safety.

In the standard electrical systems now generally used, it is necessary to employ a battery containing about seventeen (17) cells to energize the motor which operates each signal-blade, whereas in my improved mechanism it is necessary to employ only from three (3) to five (5) cells in the battery to do the corresponding work, thereby effecting an economy of over seventy-five (75) per cent. in the electrical power required and yet secure superior results.

Notwithstanding the economical and efficient operation of the mechanism, it em-

bodies all the factors of safety which practical demands in signaling mechanism, such as the quick and positive return of the signal-blade to danger should any part or parts of the signal-operating mechanism fail to work.

Other features of the invention, and the advantages thereof, will appear from the hereinafter detailed description taken in conjunction with the accompanying drawings.

In the accompanying drawings, I have illustrated different practical embodiments of the invention, but the constructions shown therein are to be understood as illustrative, only, and not as defining the limits of the invention.

Figure 1 is a side elevation, partly in vertical section, illustrating an ordinary signal blade in conjunction with a stand and a portion of a track, the full lines illustrating the signal blade at danger and the dotted lines at safety.

Fig. 2 is an enlarged vertical section through the base of the signal stand, a part of my invention being shown in vertical section and in side elevation, and one of the standard electrical operating mechanisms for the signal blade being illustrated in side elevation.

Fig. 3 is a view partly in section and partly in elevation illustrating the mechanism of Fig. 2 as viewed from the left hand side thereof.

Fig. 4 is a detail view in elevation of a part of the energy storing mechanism.

Fig. 5 is a detail section on the line 5—5 of Fig. 3 illustrating one form of clutch mechanism which co-operates with the weight lifting mechanism.

Fig. 6 is a diagrammatic view illustrating the electrical circuits which include the track, the motor and signal operating mechanism.

Fig. 7 is a sectional elevation illustrating another embodiment of the invention wherein the signal is operated and controlled mechanically in contradistinction to the electrical operating and controlling mechanism of Figs. 2, 3 and 6 of the drawings, the signal blade being shown at danger and the weight lifting mechanism having been operated so as to assist in returning said signal blade to safety.

Fig. 8 is a sectional elevation of the energy storing mechanism of Fig. 7, illus-

trating the positions assumed by the several parts when the signal blade is at safety.

I will first proceed to describe the construction of Figs. 1 to 6, inclusive, and there-
5 after set forth the signal of Figs. 7 and 8.

5 designates an ordinary signal stand erected upon a suitable foundation 6 adjacent to a railway track, the rails of which are indicated at 7, said signal stand including
10 a hollow member 5^a extending upwardly therefrom. A signal blade 9 is pivotally supported at 10 in the ordinary way upon the hollow member of the signal stand, said blade in the form of signal selected for illus-
15 tration being movable through an arc of substantially 90° and occupying a horizontal position when at danger and an upwardly extended position when at safety, see full and dotted lines respectively in Fig. 1. As
20 is usual, the signal blade is counterweighted, at 11, in order that said signal will instantly return to danger in the event of any of the operating parts getting out of order. As required by standard practice in the signal
25 art, the pivoted blade is weighted or overbalanced (not merely counterbalanced) so as to be capable of lifting a weight of blade equal to four (4) pounds in order to secure that factor of safety demanded by signal en-
30 gineers, as a result of which the signal blade will invariably and inevitably turn to the danger position in the event of sticking of any parts, or in case parts break or get out of order. The signal is moved to a safety
35 position by any mechanism ordinarily employed in the art, as will hereinafter appear. As shown in Fig. 1, a crank 12 extends from the stub shaft which constitutes the pivotal support 10 for the signal blade, said crank
40 being connected with a rod 13 which extends downwardly through the hollow member 5^a into the signal stand 5.

Speaking generally, the signal blade of Figs. 1 to 6 is moved by electrical mechanism from danger to safety, and by gravity from safety to danger, said electrical mechanism including a motor 14 incased within the lower part of signal stand 5. The motor is included in circuit with a battery 15, as
45 illustrated in the diagram Fig. 6, and this motor drives a train of gears, one of which gears, 16, is on a shaft having a pinion 17, the latter meshing with a gear 18 on a shaft 19, the latter shaft having a sprocket 20
50 which imparts movement to a sprocket chain 21, which sprocket chain extends upwardly and over a sprocket wheel 22 on a shaft 23. The sprocket chain is provided with a member 24 adapted to act upon a trigger 25 in a
55 manner to bodily elevate a lever member 26, said lever member being fulcrumed on a shaft 27 supported in a stationary frame 27^a. The lever member 26 is connected with the signal blade through mechanism which will
60 be hereinafter described, for the purpose of
65

imparting movement to said signal blade in order to shift said blade from a danger to a safety position, and as is ordinary in one type of standard electrically operated mechanism, this lever member 26 is provided 70 with suitable lever and trip devices, indicated in dotted lines in Fig. 2, in order that the lever member may be operated by a minimum expenditure of battery and motor power. One of the trip devices 28 has an 75 armature 29 adapted to be attracted by a magnet 30 which is included in the circuit of battery 15 and motor 14, for the purpose of releasing trigger 25 from a latch 25^a. The lever member 26 and signal blade 9 80 are operatively connected so that they move in unison; thus, when the signal blade 9 falls by gravity to danger, the lever member 26 also falls downward, turning on pivot 27 and assuming a downwardly inclined position, with trigger 25 in contact with member 24 on chain 21, but when the motor is energized and operates to impart movement to chain 21 and member 24, then lever member 26 is swung upwardly and the signal blade 9 85 is turned on its pivot in order to set said signal blade at safety. I have not considered it necessary to enter into a detailed description of the motor-driven mechanism herein shown for setting the signal, for the 90 reason that the construction and operation of these parts are well understood by those skilled in the art, and for the further reason that any well known or preferred mechanism may be used for imparting movement 95 to the signal blade.

Before proceeding to a description of the invention, I consider it advisable to refer briefly to the diagrammatic illustration of the electric circuits in Fig. 6, wherein the rails 7 of the track are shown in connection with a track battery 32. From one rail extends a conductor 33 to the coils of a track magnet 34, a return conductor 35 leading from the coils of the track magnet back to the other rail. This track magnet includes an armature 34^a which when attracted is adapted to make a contact 35^a, from which leads a conductor 36 to one pole of battery 15, and from the other pole of this battery 115 extends a conductor 37, which leads to a magnet of an electrically controlled brake mechanism to be hereinafter described, from which magnet extends a conductor 38 leading to a coarse winding 30^a of low resistance, 120 said coarse winding forming a part of magnet 30. From the coarse winding of said magnet 30 leads a conductor 39 to the motor 14, from which extends a conductor 40 to an automatic circuit breaker 41, 41^a, the 125 latter consisting of two spring members having contact points 42, one of said members 41 being in the path of lever member 26. The circuit breaker is open when the signal blade is raised to safety for the reason that 130

- the lever member 26 is lifted in unison with the elevation of the signal blade, so that said lever member acts on spring member 41 to lift the contact thereof free from the other 5 contact on member 41^a, whereby the motor circuit is interrupted and no current will flow from battery 15 to motor 14; but when the signal blade drops to danger and lever member 26 falls in unison therewith, then 10 lever member 26 is withdrawn from spring contact 41 and the latter springs toward member 41^a so that contacts 42 close the motor circuit, thus placing the apparatus in condition for operation under proper conditions. From member 41^a of this circuit breaker 41 extends a conductor 43, which is connected with the armature of the track magnet 34 so as to complete the circuit through the battery and the motor. 15
- 20 The magnet 30, which controls the locking and releasing mechanism for lever member 26, is provided, in addition to the coarse winding 30^a, with high resistance winding 30^b, from which extend the conductors 30^c and 30^d which are branched onto conductors 37, 43, so as to include the high resistance winding 30^b in a closed circuit with battery 15, whereby a small quantity of current will flow from this battery, through armature 34^a, conductors 43, 30^c, winding 30^b, and conductors 30^d, 37 back to the battery, for the purpose, mainly, of energizing the magnet 30 to actuate the locking devices for lever member 26 in order to contribute to the 25 safety of the signal, but should any of the wires become disconnected or the parts get out of working order, then the magnet is deenergized and the signal blade at once drops to danger. The foregoing operation 30 is usual in the electrical operating mechanisms of the type selected for illustration.
- In a general way, the signal system shown depends for operation upon a closed track circuit so that battery 32 will energize magnet 34 and battery 15 furnishes the small 35 amount of current required to energize the high resistance winding 30^b of magnet 30, the signal blade being raised into the safety position and the lever member 26 being elevated so as to lift member 41 and open the 40 circuit leading from battery 15 to motor 14. A train entering a block, short circuits battery 32 and deenergizes magnet 34, whereupon armature 34^a leaves contact 35^a and de- 45 energizes magnet 30, thus releasing lever member 26 from the restraint of its latch, whereupon the lever member 26 and signal blade 9 drop or fall, the signal blade assuming the danger position. Said signal blade 50 is thus withdrawn from member 41 and the circuit breaker closes the motor circuit, but as armature 34^a remains open by battery 32 being short circuited due to the presence of the train in the block, no current flows from 55 battery 15 to motor 14. The signal thus re-
- mains at danger so long as the train is on the block. When the block is vacated, battery 32 again energizes magnet 34, attracting armature 34^a and closing the circuit, whereupon current flows from battery 15 70 into motor 14 for the purpose of imparting movement to lever member 26, whereby the latter is raised and locked and the signal is restored to safety. 75
- A salient feature of the present invention is a movable cylinder A which is operatively connected with signal blade 9 and lever member 26. Coöperating with this movable cylinder is a piston B having a piston rod b connected with a cross member b', said cross 80 member being positioned externally to the cylinder, below the same. This cross member of the piston is connected by a chain or chains C with a weight or weights D, which weights are adapted to be lifted by 85 the movement of the piston when the signal blade moves by gravity to a danger position, whereby the energy of the signal blade when moving by gravity to its danger position is stored up due to the lifting 90 of the weights, so that the gravity of the weights will be available to assist the signal operating mechanism in moving the signal blade to safety. 95
- In the embodiment shown, cylinder A is 100 operatively connected with signal rod 13 and with an upper cross member e of a yoke E. The lower cross member e' of said yoke E is shown as having a depending boss e² to which is pivotally connected a lug 26^a 105 of lever member 26. It will be apparent that cylinder A is suspended within the yoke E, and, furthermore, that this yoke operatively connects the cylinder with lever member 26 and signal rod 13, whereby the cylinder 110 is supported for movement with lever member 26 and the signal blade. As shown, the cylinder is provided in one of its walls with an air passage F, the upper and lower ends of which terminate in ports f, f', respectively, which ports open into, or communicate with, the piston chamber at the respective sides of the piston and at the opposite limits of travel of said piston within the piston chamber. Intermediate the ends 115 of the air passage F is positioned a suitable valve adapted to control the flow of air through the passage and from one end of the piston chamber to the other, said valve being illustrated in Fig. 2 as a regulating 120 screw F' adapted to be projected across the passage F so as to control the flow of air through the passage and thereby assist in regulating the flow of air through the passage and the consequent speed of movement 125 of piston B relative to the cylinder A. 130
- The lower head of cylinder A is provided with a stuffing box b² through which extends the rod b of piston B, said piston rod being connected fixedly in any suitable way

- to cross bar b' . Chains C (or their mechanical equivalents) are attached to the respective ends of said cross bar b' , said chains extending upwardly over, and into engagement with, sprocket wheels c , and the free ends of said chains C being connected respectively to eye bolts d of weights D. The sprocket wheels are carried on shafts C' journaled in suitable bearings provided in 5
- 10 the upper free end portion of frame member G, the latter being supported in a stationary position within the chamber of signal stand 5 by rods g , or their equivalents, and said frame being braced in position by inclined 15 rods g' . Said shafts C' which carry the sprocket wheels c are provided with gears c' , and these gears mesh with pinions h of a cross shaft H, said cross shaft being journaled in bearings h' of frame member G, for 20 the purpose of supporting the cross shaft H in parallel relation to the shafts C'.
- When the signal blade moves by gravity to danger, the cylinder and lever member 26 move downwardly in unison with the drop 25 of said signal blade, for the reason that the signal rod 13 and the lever member 26 are connected rigidly by the yoke E and, further, the cylinder A is attached rigidly to the yoke E. The downward travel of cylinder A with respect to piston B compresses air within the upper part of said cylinder, between the upper cylinder head and the piston, and during the downward travel of the cylinder the air compressed within said 30 cylinder attains such pressure that it overcomes the ponderosity of the weights D and forces piston B down. The descent of the piston and its member b' draws upon the chains C and elevates weights D, whereby 35 the said weights are adapted to be used upon the subsequent operation of the signal operating mechanism, for the purpose of assisting the signal operating mechanism to return the signal from danger to safety.
- 40 45 During the period which elapses between the fall of the signal blade to danger and the return of said signal blade to safety, it is desirable to retain the weights, the piston and cylinder in the positions into which they are moved, thus relieving the piston and cylinder from the ponderosity of the weights. To this end, I have provided an automatic 50 brake mechanism which co-operates with a part of the weight lifting mechanism, said 55 brake mechanism being controllable by a magnet which is included in the circuit of the battery and the motor. Various forms of retaining or brake devices may be employed for the purpose of relieving the piston 60 and cylinder from the ponderosity of the weights, but as shown, cross shaft H is provided with a brake member I in the form of a chambered disk. Said disk is mounted loosely on the shaft H to turn freely in one 65 direction thereon, but with this brake mem-

ber is associated a clutch consisting of a cam disk i and a series of clutch rollers i' , see Fig. 5.

The cam disk and the clutch rollers are so related to each other and the brake disk I 70 that at one period of operation the shaft H and the gears c , c' , h and shafts C' are free to rotate while the brake disk is held stationary by the action of the brake shoe on the brake disk, as when the piston is forced 75 downward to elevate the weights; but at other periods of operation, the rollers and cam disk co-operate in making the brake disk fast with said shaft H, whereby on the elevation of the weights the brake mechanism 80 supported by frame G operates to lock the weights in raised positions and the ponderosity of the weights is removed for the time being from the piston and cylinder. But upon the removal of the braking pressure 85 from disk I, the latter and the gears are free to rotate so as to permit the descent of the weights which act to impart movement to the piston in order to lift the latter quickly for compressing air within the cylinder, thus 90 performing the important function of accelerating the speed of the signal blade when returning to safety. With the brake disk I 95 co-operates a brake shoe J, the latter having a working surface J formed by some suitable friction material. This brake shoe is connected pivotally with a brake lever J' , fulcrumed at j' to frame member G, said brake lever being under the control of a suitable retractor, such as spring J^2 , for the purpose 100 of impelling the brake lever normally toward the brake disk I, whereby the brake shoe engages normally with the brake disk owing to the action of the retractor J^2 , for the purpose of normally applying the brake 105 to arrest the movement of shaft H. The brake lever is operated electrically to release the brake, and to this end, said brake lever is provided with an armature k adapted to be attracted by a magnet K, the coils of 110 which are connected by conductors 37, 38 in the circuit which includes the motor 14 and battery 15, whereby the flow of current from the battery to the motor energizes magnets 30 and K, the latter acting to release the 115 brake mechanism simultaneously with the operation of motor 14 to impart movement to the lever member 26 of the signal operating mechanism. Magnet K for releasing the brake mechanism is positioned below 120 brake lever J' , and it is supported by a bracket k' attached to frame member G, whereby magnet K is positioned and supported in co-operative relation to the movable parts of said automatic brake. 125

Piston B is of any suitable construction, the same being shown as an ordinary piston head provided with packings and with a central hub to which is attached the piston rod. It is preferred to employ a piston hav- 130

ing a port l which is normally closed by a valve L , the stem of which is enveloped by a coiled spring l' . A relative movement of the piston and cylinder in one direction 5 seats the valve so that air will pass through the piston from one side thereof to the other side, but movement of the piston and cylinder in an opposite direction will compress air between the piston and one cylinder head 10 in a manner for the air pressure to close valve L as will presently appear.

The operation of the energy storing mechanism in connection with the signal blade and signal-operating member 26 is as 15 follows:—Assuming that the signal blade is in the raised position shown by dotted lines in Fig. 1 to indicate safety, and that a train enters the block, battery 32 is short circuited to deenergize magnet 34 and release lever member 26, whereupon the signal blade drops by gravity to danger and lever member 26 turns on pivot 27 to a downwardly inclined position. The fall of the signal 20 and the lever member forces cylinder A 25 downward relative to piston B, as a result of which air is compressed between the upper cylinder head and the piston, thereby checking the sudden movement of the parts for the reason that the piston and cylinder 30 serve the functions of a dash pot in the relative movement of the cylinder to the piston. At this time valve L is closed, and the air rushes through passage F, past valve F' , flowing from the upper part of the piston chamber to the lower part thereof, but 35 it is not necessary that the cylinder shall descend its full length. Now this relative movement of the cylinder to the piston, occasioned by, and due to, the gravity movement 40 of the signal blade brings into action the weight lifting mechanism as follows:—The descent of the cylinder relative to the piston compresses air within the upper part of the cylinder, and such compressed air 45 exerts pressure upon the piston. As the pressure increases to a point sufficient to overcome the ponderosity of the weights, the piston is forced downward within the cylinder, and thus the descent of the piston 50 forces cross member b' downward and draws upon chains C, thereby elevating weights D the distance desired. At this time, brake member I remains at rest, being 55 in frictional contact with brake shoe J which is under the control of retractor J^2 , the magnet K remaining inert or passive for the reason that no current flows through it; but the movement of chains C in elevating the weights D takes place freely for the 60 reason that clutch member i is free to turn relative to clutch rollers i' when the sprockets c , gears c' , shafts C', gear h , and shaft H are rotated by the movement of the chains, as described.

65 It will be manifest that the movement of

the signal blade, transmitted through the cylinder and piston, will thus operate to lift the weights, said cylinder and piston acting as a dash pot to check the momentum of the signal blade. When the weights are raised, 70 the clutch member i and rollers i' coöperate with shaft H, brake I, shoe J, lever J' and retractor J^2 in retaining the weights in such elevated position, and thus the ponderosity of the weights is not borne by, or 75 imposed upon, the cylinder and piston directly. The signal blade, and devices coöperating therewith, remain in the described positions so long as the block is occupied by a train, but when the block is vacated, 80 then the following operations take place:—Battery 32 energizes magnet 34 and armature 34^a closes the circuit through battery 15 and motor 14, the lever member 26 having previously dropped to a downwardly inclined position so as to allow circuit breaker 41, 41^a to close and to bring trigger 25 into contact with member 24 on motor driven chain 21. Now when the train moves out of the block, and the motor circuit is closed, 85 current flows through magnet K so as to attract armature k for the purpose of moving brake lever J' against the tension of retractor J^2 and withdrawing shoe J from brake disk I, thus releasing the weights 90 from the restraint of the automatic brake: At such time, the motor 14 acts upon lever member 26 to restore the signal blade to safety, and this operation of the motor is assisted or supplemented by the gravity of 95 the weights D. Said weights having been made free from the restraint of the brake, at once drop, pulling down the chains and elevating the piston within the cylinder, thereby compressing air between the piston and the upper cylinder head, the valve L being closed. The upward impulse thus given to the piston by the gravity movement of the weights, exceeds the upward speed of movement imparted to the cylinder by the action 100 of the motor through chain 21, member 24, lever member 26 and yoke E, as a result of which the air compressed in the cylinder by the action of the piston imparts an increased speed or accelerates the travel of the 105 cylinder, whereby the coöperating weights and piston not only supplement the action of the motor in returning the signal blade to safety but the speed of movement of the cylinder and the signal blade is accelerated. 110 I am thus able to restore the signal blade to safety at a much faster speed, within much less time, than is ordinarily possible, but what is of greater importance, I am enabled to effect a very considerable saving in 115 the battery power required to energize the motor, for the reason that the energy of the weights D is utilized to compress air in the cylinder, and this compressed air imparts an impulse to the cylinder in a direction to 120

re-set the signal, whereby a battery consisting of a comparatively few cells may be employed to furnish the power required to operate the motor. When such upward movement of the piston relative to the cylinder takes place, the air compressed in the cylinder flows from the upper end of the piston chamber, through passage F, and into the lower end of the piston chamber, whereby the flow of air is checked by the small diameter of passage F, but such flow of air through the passage may be controlled by an adjustment of valve F', thus regulating the speed of movement of the cylinder in re-storing the signal blade to safety.

Figs. 7 and 8 of the drawings illustrate a mechanically operated and controlled signal embodying the salient features of the present invention. The signal blade 9 is of that type which moves through an arc of 60°, from safety to danger, and vice versa, the blade assuming a downwardly inclined position when at safety and a horizontal position at danger. Said blade 9 is counterbalanced at 11 and fulcrumed at 10 upon stand 5, and to this signal blade is connected an operating rod 13. As shown, this rod is attached at its lower end to a lever 45 fulcrumed by a bolt 46 upon a bracket 47 of stand 5. Said lever carries a weight 48, and to the free end of the lever is pivoted the upper portion of a rod 49, the lower end of which is pivoted to a bell crank 50, from which extends a rod 51 leading to a tower or any other place convenient for the operation of the signal. Coöperating with the weighted lever 45 is movable cylinder A and piston B, said movable cylinder being directly connected with the lever by a rod 52, one end of which is pivoted directly to the lever and the other end connected fixedly to the moving cylinder. This cylinder is provided with an air passage F, the flow of air through which is regulated by a controlling valve F'. The piston B operates within the cylinder, said piston having a rod b extending through the lower head of the cylinder. To this piston rod is attached a chain C, which runs over a pulley 53, supported on the signal stand, said pulley 53 being the mechanical equivalent of the sprocket wheel c, over which runs one of the chains C in the embodiment of the invention shown in Figs. 2, 3 and 4. The chain C is connected at its other end to a weight D, but, if desired, two chains and two weights may be associated with the piston rod b of Figs. 7 and 8 in the same way as the corresponding chains and weights are combined with the piston rod and the cross member b' in the construction of Figs. 2 to 4, inclusive. As a means for relieving the ponderosity of the weights from the piston and the cylinder, when said weights shall have been raised by the gravity movement

of the signal blade to danger, I have provided the following mechanism, the same being considered the equivalent of the electrically operated brake mechanism employed in the construction of Figs. 2 to 5, inclusive, viz: The rod 49 is provided intermediate its ends with a shoe m, which is adapted to engage with the free end of a trip M, the latter being pivotally supported on the signal post 5. The piston rod b extends downwardly a suitable distance below the cylinder, the lower end of said rod being guided in a lug n, of a bracket N, fixed to the signal post, and on this piston rod is secured a locking member O, the same being shown as having a series of ratchet teeth o. With this ratchet face of the locking member coöperates a pawl P, the same being pivotally supported at p on the bracket N. A spring P' normally impels the pawl into the path of the ratchet teeth on the locking member O, so that the pawl will engage with the locking member when the piston rod moves in a downward direction upon the elevation of weights B, whereby the pawl acts to restrain the member O and the piston rod from movement in an upward direction by the weights, and thus the piston and the cylinder are relieved from the ponderosity of the weights. The pawl is released automatically from the locking member at the proper interval of time by an operative connection of said pawl with the trip M, said operative connection being shown as a link Q, one end of which is pivoted to an arm of pawl P, whereas the other end of the link is pivoted to the trip M, the movement of which trip is effected by contact with the shoe m on rod 49 when said rod is actuated by bell crank 50 and rod 51 so as to withdraw the dog from the locking member at a time just prior to the return of the signal from danger to safety, which return movement of the signal to safety is facilitated by the coöperation of the piston with the cylinder, as a result of which a minimum effort is required to return the signal to safety position and the speed of setting the signal to said safety position is materially increased.

It will be noted that the signal shown in Figs. 7 and 8 pertains to a different type from that illustrated in Figs. 1 to 6, inclusive, the main differences being that the signal blade is weighted to rise to danger and be positively lowered to safety and that it moves through an arc of substantially 60° so as to be inclined when at safety.

The operation of the signal illustrated in Figs. 7 and 8 is as follows:—With the signal blade 9 at danger, Fig. 7, cylinder A and piston B were previously operated to raise weight D, and pawl P is in engagement with locking member O to relieve the piston from the direct pull of the weights. To restore the blade to safety, bell crank 50

is operated in the usual way by a towerman, or through any other agency, thus pulling down on rod 49, starting to raise weighted lever 45, and moving shoe *m* into engagement 5 with trigger *M*, the latter being shifted to withdraw dog *P* from member *O*. The piston is thus released from the restraint of the locking mechanism, whereupon weight *D* pulls down the chain and lifts the piston 10 within the cylinder. The operations of tripping the dog and releasing the weight take place quickly, and although cylinder *A* begins to ascend with the weighted lever and to move in unison with the signal blade, still 15 the weight *D* imparts such a quick impulse to piston *B* that the speed of the piston within the cylinder exceeds the upward movement of said cylinder under the action of lever 45, as a result of which air is compressed 20 between the piston and the upper cylinder head, which compressed air in turn acts upon the cylinder head so as to impart to the cylinder a sudden upward movement, whereby the conjoint action of the cylinder 25 and piston due to the quick drop of the weight assists to a very marked extent the operation of lever 45 in restoring the signal blade to safety. The mechanism contributes a very material amount of energy to the operation 30 of the ordinary mechanism in re-setting the signal, thus making it easy for the signal operator to restore the signal, but a marked advantage of my device is that the speed of re-setting the signal is increased 35 to a substantial extent owing to the air within the cylinder being compressed by the movement of the piston, which air reacts upon the cylinder to accelerate the upward movement thereof. The speed of 40 the cylinder is controllable by adjustment of valve *F'* to regulate the flow of air through passage *F*.

With the signal blade at safety, the parts of the energy storing mechanism occupy the 45 positions of Fig. 8, wherein the weighted lever and the cylinder are raised, the chain and weight lowered, and the piston pulled upward until arrested by a stop *s* on the piston rod *b* abutting the bracket. When the 50 signal blade moves to danger, from any cause, lever 45 and cylinder *A* are quickly lowered, thus raising rod 49 and shoe *m* so as to release trigger *M* and allow spring *P'* to throw dog *P* into the path of toothed 55 member *O*. The quick descent of cylinder *A* compresses air within the upper part of the piston chamber, the outflow of air through passage *F* being controlled by valve *F'*, whereby the compressed air acting 60 upon the piston forces the latter downwardly within the descending cylinder. Such downward movement of the piston pulls on the chain and elevates the weight to the position of Fig. 7, and the toothed 65 member *O* engages automatically with dog

P so as to lock the weight in a raised position and to arrest the piston from movement within the cylinder, although said cylinder is capable of movement relative to the piston upon the subsequent operation of restoring the signal blade to safety. 70

The type of signal shown in Figs. 7 and 8 is known as a mechanically operated signal wherein the signal blade is moved positively into the danger position as well as the safety 75 position, but in case of breakage of the parts the signal blade is weight controlled so that it will return to danger by gravity automatically and instantaneously.

It should be stated that when my invention is embodied as a part of the electrically operated signal setting mechanism of Figs. 2 to 6, inclusive, the motor and other parts can be reduced in size to a substantial extent, for the reason that the energy storing 80 mechanism of this invention furnishes such an amount of power that not only is it possible to decrease the cells of the battery, but the motor, gearing and other parts may, also, be decreased in size. 85

It is to be understood that the piston *B*, in either of the two forms of mechanism herein disclosed, should be provided with the valve *L*, the latter serving the purpose, mainly, of an escape valve whereby air may 90 flow through the piston under the following conditions: The gravity movement of the signal blade and the consequent movement of the cylinder involves two consecutive periods of movements in order to absorb the shock due to the momentum of the parts and to fully restore the signal blade to its danger position. At the first period of movement of the signal blade under the ponderosity of its counterweight 11 to shift 100

said signal blade to the danger position, the cylinder moves quickly in a downward direction for a part of its stroke, which downward movement is checked by the compression of air between the upper cylinder head 110 and the piston, the latter at such period being stationary relatively to the cylinder. The air thus compressed acts upon the piston to depress the latter and thus elevate the weights for storing energy as has been explained. The by-pass *F* permits the air to escape from the upper part to the lower part of the cylinder, the flow of air being regulated by adjustment of the valve *F'* so that there is always made provision for 115 the flow of air, and should anything happen to the working parts of the signal mechanism which would make it necessary to use the full force of the counterweight 11 in moving the signal blade to danger, the air 120 is free to escape from the upper to the lower part of the cylinder and thus the signal blade will slowly return to the normal or danger position under the full force of its counterweight. 125

It is apparent that when the signal blade moves under the action of its counterweight to the danger position, the cylinder must travel downward for an appreciable distance before a sufficient amount of air is compressed above the piston for lifting the energy storing weights, and when the parts (the cylinder and the piston) come finally to rest, there is an appreciable space between the lower head of the cylinder and the piston. Now when the cylinder is moved upwardly by the action of the motor to begin the operation of moving the signal blade from the danger position to the safety position, the piston will still occupy a position an appreciable distance above the lower cylinder head. The brake having been released and the weights having acted to impart the upward impulse to the piston in order to compress the air in the upper part of the cylinder and thereby accelerate the upward movement of the cylinder, it is apparent that the piston will reach the end of its upward stroke and will be at rest while the cylinder still continues to move upwardly under the power of the motor, in order to return the cylinder and the signal blade to their fully restored positions. Such continued upward movement of the cylinder after the piston makes the full limit of its upward travel, results in the compression of air between the piston and the lower cylinder head, the presence of which compressed air would tend to retard the continued upward movement. This is overcome by the presence of the valve L in the body of the piston, which valve is opened automatically by the pressure of air below the piston, so as to act as a relief to the air pressure, whereby the cylinder is permitted to move upwardly under the power of the motor until the cylinder reaches its final position in an upward direction, and the signal blade is returned to a fully restored safety position. This leaves the cylinder and piston in the most effective positions for the further operation of restoring the signal blade to safety under the conditions described.

Although I have shown and described the power transmitter consisting of cylinder A and piston B as adapted for compressing air, it will be manifest to those skilled in the art that any fluid may be used in the power transmitter.

As hereinbefore stated, the energy storing mechanism of this invention may be used in connection with any of the usual types of signals, two forms of which are shown. Furthermore, while I have particularly shown and described the energy storing mechanism as adapted for the work of resetting the signal blade to safety, it is manifest that the energy stored by such mechanism may be utilized for other pur-

poses, such as operating other signals on sidings, and for the operation of audible signals, etc.

Should any part of the weight lifting mechanism get out of order for any reason, the signal blade is still free to drop by gravity to danger, for the reason that the weight imposed upon the cylinder will act to depress said cylinder, the air leaking slowly through passage F and past valve F', and flowing slowly from the upper part into the lower part of the cylinder, whereupon the cylinder descends without moving the energy storing weight, the net result being to permit the cylinder to descend when the signal blade moves to danger owing to the presence of the passage F in the cylinder.

Having thus fully described the invention, what I claim as new, and desire to secure by Letters Patent is:

1. In a signal, the combination with a signal blade mounted for movement freely by gravity to one of its indicating positions, and operating means for effecting positively a return movement of said signal blade to another of its indicating positions of elastic-fluid mechanism for storing energy developed by a rapid gravity movement of said signal blade, said elastic-fluid mechanism coöperating with said operating means for accelerating the return movement of said signal blade.

2. In a signal, an overbalanced signal blade mounted for unrestrained movement by gravity to one of its indicating positions, operating means for imparting a reverse movement to said signal blade, and energy-storing means connected with the signal blade and with said operating means, said energy-storing means being operated by the unrestrained and rapid gravity movement of the signal blade and said energy-storing means coöperating with said operating means in the subsequent action thereof when returning the signal blade to another of its indicating positions.

3. In a signal, the combination of a signal-blade, a movable cylinder coöperating with the blade, a movable piston operating within the cylinder, and energy storing means, adapted to receive energy from the movement of the signal-blade, for actuating said cylinder and piston.

4. In a signal, the combination with a signal blade, of a cylinder movable with said blade, a piston operatively positioned for movement within said cylinder, and a weight controllable by the movement of said piston, said parts being operated by a gravity movement of the said signal blade for storing energy.

5. In a signal, the combination with a signal blade movable by gravity to one position, and operating means for im- 130

- ing a reverse movement thereto, of an elastic-fluid device embodying a coöperating piston and cylinder, one of which parts is connected with said signal blade for movement therewith, and energy storing means connected with the other of said parts of the elastic-fluid means.
6. In a signal, the combination with a signal blade movable by gravity to one position, and operating means for imparting a reverse movement thereto, of an elastic-fluid device embodying a coöperating piston and cylinder, one of which parts is connected with said signal blade for movement therewith, a weight operated by the movement of the other of said parts of said elastic-fluid means, and means for relieving the cylinder and the piston from the effect of said weight.
- 10 7. In a signal, the combination with a signal blade, of a cylinder to which movement is imparted by gravity movement of the signal blade, a piston coöperating with the cylinder, a weight operated by a movement 20 of the piston relatively to the cylinder, and means for relieving the piston from the action of said weight.
8. In a signal, a signal member adapted to be moved by gravity to one of its indicating positions, means for imparting a reverse movement thereto, a coöperating cylinder and piston each of which is movable with relation to the other and one of which is actuated directly by the gravity movement 30 of the signal member, and means influenced by the compression of air within the cylinder due to such relative movement between the piston and cylinder for storing up energy developed by the gravity movement 35 of said signal member.
- 40 9. In a signal, the combination with a signal blade free to move by gravity to one of its indicating positions, of an elastic fluid power transmitter embodying two members free to move relatively to each other, one of said members being operated by a gravity movement of the signal blade, operating means for imparting a return movement to the signal blade, and energy storing means controlled by the other member of said power transmitter, said energy storing means coöperating with said operating means in accelerating the return movement 45 of the signal blade.
- 50 10. In a signal, a signal member adapted to be moved by gravity to one of its indicating positions, means for imparting a reverse movement thereto, a coöperating cylinder and piston mechanism operated by said signal member, and means operable by said cylinder and piston mechanism for storing energy developed by the gravity movement 55 of said signal member.
- 60 11. In a signal, a signal member adapted to be moved by gravity to one of its indicating positions, means for imparting a reverse movement thereto, a coöperating piston and cylinder mechanism operated by the signal member, and means actuated by said piston and cylinder mechanism for storing 70 energy developed by the gravity movement of said signal member, said energy storing mechanism and the piston and cylinder mechanism being subsequently effective in moving the signal member to another of its 75 indicating positions.
12. In a signal, a signal member adapted to be moved by gravity to one of its indicating positions, means for imparting a reverse movement thereto, a cylinder movable in unison with said signal member, a piston coöperating with said cylinder, means for controlling the flow of air within the cylinder set in motion by a relative movement of the piston and cylinder, and reserve power means 80 controllable by the compression of air established within the cylinder upon the gravity movement of the signal member.
13. In a signal, a signal member movable by gravity to one of its indicating positions, 90 a coöperating cylinder and piston mechanism whereof the cylinder is movable in unison with said signal member, and reserve power mechanism actuated by the compression of air established within the cylinder upon the 95 gravity movement of said signal member.
14. In a signal, a signal member movable by gravity to one of its indicating positions, a cylinder and piston mechanism whereof the cylinder is connected with the signal member 100 for movement in unison therewith, and a weight controllable by the piston, to which piston movement is imparted by the air compressed in the cylinder when the signal member is moved by gravity to said indicating 105 position.
15. In a signal, a signal member movable by gravity to one of its indicating positions, a coöperating cylinder and piston, said cylinder being movable in unison with said signal 110 member, and a weight coöperating with said piston and adapted to be raised by the movement of said piston relative to the cylinder due to the compression of air within the latter when the gravity movement of said signal member takes place.
16. In a signal, the combination with a gravity operated signal blade, an air compressing mechanism operated by the gravity movement of said signal blade, and means 120 actuated by the air compressing mechanism for storing energy developed by said gravity movement of the signal blade.
17. In a signal, the combination with a gravity operated signal blade, means for imparting a reverse movement thereto, air-compressing mechanism operated by said signal blade, means actuated by said air compressing mechanism for storing energy developed 125 by the gravity movement of said signal blade, 130

- and means whereby the stored energy is rendered subsequently effective in the operation of moving the signal blade to another of its indicating positions.
- 5 18. In a signal, the combination with a gravity operated signal blade, of an air-compressing means connected with said signal blade for operation thereby, a weight adapted to be raised by the operation of said air-compressing means when the gravity movement of the signal blade takes place, and mechanism whereby the energy of the weight is rendered available in imparting movement to said signal blade subsequent to the gravity movement thereof. 70
- 10 19. In a signal, the combination of a signal blade movable by gravity to danger, an air compressing means operated by such gravity movement of the signal blade, a weight adapted to be raised by the operation of said air compressing means when the signal blade is operated by gravity, and means operable to utilize the energy of the weight in subsequently moving the signal blade to safety. 75
- 15 20. In a signal, the combination of a signal blade movable by gravity to danger, an air-compressing means operable by said signal blade upon the gravity movement thereof, means actuated by the air-compressing means for storing energy developed by such gravity movement of the signal blade, and signal setting means adapted to utilize the energy of said storing means in subsequently imparting movement to the signal blade for restoring the latter to safety. 80
- 20 21. In a signal, the combination of a gravity operated signal blade, an air-compressing means connected therewith and operable upon the gravity movement thereof for compressing air, a weight, means actuated by the compression of air within said air-compressing means for lifting the weight, and means whereby the energy of the weight is subsequently rendered available in imparting movement to the signal blade in a reverse direction to the gravity movement thereof. 85
- 25 22. In a signal, the combination of a signal blade movable by gravity to one position, an air compressing means operated by said signal blade upon the gravity movement thereof, a weight, means actuated by the compression of air for raising said weight, means for utilizing the energy of said weight in subsequently imparting movement to said signal blade, and means for retaining the weight in its raised position without imposing the ponderosity thereof upon said air compressing means. 90
- 30 23. In a signal, the combination with a signal blade, of an air-compressor operable by a gravity movement of said signal blade, a weight, said weight being lifted by the compression of air by said air compressor, retaining means for said weight, and means for releasing said weight from the action of the retaining means, said weight and air compressor coöperating with the signal during the movement of the latter to one of its indicating positions. 95
- 35 24. In a signal, the combination of a signal blade movable by gravity to one position, an air compressing mechanism operated by said signal blade upon the gravity movement thereof, a weight, means actuated by the compression of air for raising said weight when the gravity movement of the signal blade takes place, and means adapted to utilize the gravity movement of the weight in compressing air within the air compressing mechanism for subsequently imparting an accelerated speed to the signal blade in a reverse direction to that in which the signal blade moves when actuated by gravity. 100
- 40 25. In a signal, the combination of a signal blade movable by gravity to one position, an air-compressing mechanism connected with said signal blade, a weight, means for elevating the weight when air is compressed within said air-compressing mechanism by the gravity movement of said signal blade, and means for utilizing a gravity movement of the weight in subsequently compressing air within said air compressing mechanism whereby the latter is actuated by the weight to accelerate the speed of the signal blade and for moving the latter to another of its indicating positions. 105
- 45 26. In a signal, the combination of a signal blade movable by gravity to one position, air-compressing mechanism operated by the gravity movement of said blade, and means operated by the air compressing mechanism for storing energy, said energy storing means acting subsequently through said air compressing mechanism for compressing air therein whereby the compressed air within said air compressing mechanism imparts movement at accelerated speed to said signal blade and in an opposite direction to that in which the signal blade is actuated by gravity. 110
- 50 27. In a signal, the combination of a signal blade movable by gravity to one position, an air-compressing means embodying a piston and a cylinder the latter of which is operated by the gravity movement of the signal blade, a weight connected to the air-compressing piston, and means whereby the energy of the weight acts to impart movement to the piston for compressing air in the cylinder subsequent to the gravity operation of the signal blade, whereby the air-compressing means is adapted to operate the signal blade at accelerated speed and in a reverse direction to the gravity movement thereof. 115
- 55 28. In a signal, the combination of a signal blade movable by gravity to danger, an air compressor operable by a gravity movement of said signal blade, a weight, said weight being lifted by the compression of air by said air compressor, retaining means for said weight, and means 120
- 60 65

air-compressing means connected with said signal blade, a weight adapted to be raised by the operation of the air-compressing means upon the gravity movement of the signal blade, and means operated by the fall of the weight for compressing air whereby said air-compressing means actuates to return the signal blade to safety at accelerated speed.

29. In a signal, the combination of a signal blade movable by gravity to one position, an air compressor the cylinder of which is connected with said signal blade, a weight operated by the descent of the piston due to the compression of air within the cylinder upon the gravity movement of the signal blade, means for retaining the weight in a raised position, and means for releasing the retaining means whereby the weight actuates the piston and the latter compresses air within the cylinder for imparting movement to the signal blade in a reverse direction and at an increased speed.

30. In a signal, the combination of a signal blade movable by gravity to one position, an air compressor embodying a co-operating cylinder and piston and the cylinder of which is connected with said signal blade, a weight mechanically connected with the piston and adapted to be elevated by a movement thereof due to the pressure of air established within the cylinder upon the gravity movement of the signal blade, retaining means whereby the weight is held in said elevated position, and signal setting devices including means for releasing said retaining means whereby a gravity movement of the weight actuates the piston to subsequently compress air with the cylinder for imparting movement at accelerated speed to the signal blade, thereby shifting the latter to another of its indicating positions.

31. In a signal, the combination of a signal blade movable by gravity to one position, electrically operated means for imparting a reverse movement to said signal blade, an air compressor operated by the gravity movement of said signal blade, a weight, and means operated by said compressor for elevating said weight.

32. In a signal, the combination of a signal blade movable by gravity to one position, electrically operated means for imparting a reverse movement to said signal blade, an air-compressor connected mechanically with said signal blade, energy storing means operated by the air compressor upon the gravity movement of the signal blade, and means whereby the energy of said storing means is adapted to supplement the electrically operated means when imparting the reverse movement to the signal blade.

33. In a signal, the combination of a signal blade movable by gravity to one position, electrically operated means for imparting a

reverse movement to said signal blade, an air compressor connected mechanically with said signal blade, a weight adapted to be lifted by said air compressor upon the gravity movement of said signal blade, and means whereby a gravity movement of the weight is utilized for subsequently compressing air whereby said air compressor acts in conjunction with the electrically operated means in imparting reverse motion to the signal blade and at accelerated speed.

34. In a signal, a signal blade movable by gravity to danger, electrically operated means for imparting reverse motion to said signal blade, an air compressor operated by the gravity movement of the signal blade, a weight adapted to be elevated by said air compressor, and means for subsequently releasing the weight whereby the energy of said weight is applied to subsequently compress air and said air compressor co-operates with the electrically operated means in imparting reverse motion and at accelerated speed to the signal blade when returning the said signal blade to safety.

35. In a signal, the combination of a signal blade movable by gravity to one position, electrically operated means for imparting reverse movement thereto, an air compressor connected with said signal blade, a weight adapted to be raised by the operation of the air compressor upon the gravity movement of the signal blade, and electrically operated retaining means co-operating with said weight and adapted to release the same, whereby the fall of the weight actuates the air compressor to compress air which is applied in conjunction with said electrically operated means in imparting reverse motion and at increased speed to the signal blade.

36. In a signal, the combination of a signal blade movable by gravity to one position, electrically operated means for imparting reverse movement thereto, an air compressor connected with said signal blade, and movable in unison therewith, a weight, lifting means operated by the air compressor and adapted to elevate the weight upon the gravity movement of the signal blade, a brake for restraining said lifting means from movement, and means operable in unison with the electrically operated means for releasing said brake whereby the weight is free to actuate the motor in accelerating the reverse movement of the signal blade.

37. In a signal, the combination of a signal blade, operating means for imparting movement in one direction thereto, an air compressor operable by a gravity movement of said signal blade, a weight, lifting means co-operating with the air compressor and the weight, and restraining means for relieving the air compressor from the effect of said weight.

38. In a signal, the combination of a sig-

- nal blade movable by gravity to one position, means for imparting reverse motion thereto, an air compressor the cylinder of which is connected with the signal blade for movement in unison therewith, a weight, lifting means coöperating with the weight and the compressor piston, and automatic brake mechanism for retaining the weight in the position to which it is elevated by the compressor when the latter is actuated by the gravity movement of said signal blade, said brake mechanism being releasable prior to resetting the signal blade, whereby the weight is released and actuates the compressor piston for compressing air within the cylinder for the purpose of imparting reverse motion and at accelerated speed to said signal blade.
39. In a signal, the combination of a signal blade movable to a plurality of indicating positions, means for setting the signal blade, a power transmitter operated by the movement of the signal blade to one of its indicating positions, a weight adapted to be lifted by the operation of said power transmitter, and means for releasing the weight whereby the energy of the weight is applied to coöperate with said signal setting means in moving the signal blade to another of its indicating positions.
40. In a signal, the combination of a signal blade movable to a plurality of indicating positions, means for setting the signal blade, a power transmitter operated by the movement of the signal blade to one of its indicating positions, a weight adapted to be lifted by the operation of said power transmitter, and means actuated by the signal setting means for releasing the weight

whereby the energy of the weight is applied 40 through said power transmitter to coöperate with said signal setting means in moving the signal blade to another of its indicating positions.

41. In a signal, the combination of a signal blade movable to a plurality of indicating positions, means for setting the signal blade, a power transmitter operated by the movement of the signal blade to one of its indicating positions, said power transmitter embodying a movable cylinder having an air passage, a piston movable therein, and an automatic valve movable with said piston for relieving the air pressure in one direction, a weight adapted to be elevated by the 55 operation of the power transmitter when the signal blade moves to one position, and means for releasing the weight whereby its gravity fall is applied through the power transmitter to coöperate with the setting 60 means in moving the signal blade to another of its indicating positions.

42. In a signal, a signal blade movable to a plurality of indicating positions, means for setting the signal blade, a cylinder to 65 which movement is imparted by the signal blade, a piston, a weight controlled by the movement of the piston, and means whereby air is permitted to leak from said cylinder when the signal blade moves to one indicating position.

In testimony whereof I have signed my name to this specification in the presence of two subscribing witnesses.

JAMES T. HAMBAY.
